ALFRED ERNEST HUDD, OF LIVERPOOL, AND ARTHUR FRANK BOUND, OF TIMPERLEY, ENGLAND, ASSIGNEES, BY MESNE ASSIGNMENTS, TO AUTOMATIC ELECTRIC INC., OF CHICAGO, ILLINOIS.

TRAIN-CONTROL SYSTEM.

Application filed October 29, 1921, Serial No. 511,322, and in Great Britain November 18, 1920.

The present invention concerns improvements in or relating to train control systems. In order that such systems should be of general application, it is important that in addition to being reliable and efficient, they should be simple and avoid any undue interference with the normal running of the trains, while in addition, the cost of the apparatus should not be unduly high. It is also important that the apparatus should meet varying conditions in different places and should operate equally effectively at all times. One arrangement is to provide a ramp or tripping device at the distant signal so that if this signal is at "danger," a service application of the brake is applied, while if the home signal is still at "danger" when reached, an emergency application of the brake is applied.

This arrangement fails, because the engine may be running at too great a speed when passing the home signal (due to neglect or a mistake on the part of the driver) to be pulled up in time to avoid an accident, although the emergency application is applied. It is therefore important that the home signal should not be passed at an excessive speed. Again, an engine driver should have complete liberty to speed up his train as soon as the home signal is lowered, and therefore any limitation placed on the train to reduce its speed, prior to reaching the home signal should be removable as soon as the home signal is lowered.

In order to obtain these objects, one of the features of the present invention is that the point at which the brakes are applied to the train is rendered dependent upon its speed, so that it can always be pulled up within the regulation block clearance beyond the home signal. Preferably two brake controlling elements are provided, one as usual at the home signal which would pull up within the block clearance a train travelling at say, 30 miles an hour, whereas, the other application would be applied to trains exceeding this speed at a point where the fastest train could be pulled up within the block clearance.

It will thus be seen that the emergency application is only applicable if a train is at a distance from the home signal and travelling at such a speed, that unless the brake is immediately applied, the train will

pass beyond the regulation block clearance with the home signal at "danger."

Briefly, the rules governing the invention may be summarized in the following statement:—The distance run by the fastest train beyond the home signal, assuming that such a train had the emergency application of the brakes applied at a predetermined position, should equal the distance run by a slow train which has its brakes applied at the home signal and which is running at such a speed as to just permit it passing the predetermined position without having its brakes applied. By this means having the necessary data for any particular location, the position at which the first emergency application may be applied, can be readily obtained.

By varying the point of application according to the speed of the train, a reduction may be made in the standard block clearance operating on English railways, so adding to the track capacity of the same, whereas, existing known systems would, if absolute safety is to be secured, necessitate the block clearance being considerably increased as trains travelling at high speeds on a falling gradient might travel a distance well over 100% in excess of block clearance when not tripped till passing the home signal itself.

Another feature of the invention consists of a time element device adapted to be used for determining the speed of a train and for controlling the application of the brakes if the train passes between two points in less than a predetermined time.

According to the invention the time element is adapted to be set in operation against a continually acting restoring force when the train passes a certain point, and is subsequently maintained in operation while the train passes over a given track. By its operation it causes the brakes to be applied if the train reaches a given point before a predetermined time, while after the train has left the track the time element device is adapted to be automatically restored to normal. Such an arrangement is applicable for use either at the turn out of a junction or where the configuration of the line is a sharp curve or other place where a permanent speed reduction is required, while it is further applicable for use in connection

with train control systems in which it is required to bring the train to rest within a given block clearance as described above, when in such a case, the application of the 5 brakes would be jointly under the control of the signalling system and the time element device, so that if the signals were clear, the brakes would not be applied, the time element device being only operable if 10 the signals are at "danger."

In the preferred form of the invention track circuits are provided which are controlled by the train for effecting the application of the brakes if the train should exceed 15 a predetermined speed, while another feature of the invention is a time element device controlled by periodic movement. By way of example, a preferred form of carrying the invention into effect will be described 20 although it will be understood that considerable modifications may be made therein by those versed in the art without departing from the spirit of the invention.

Referring to the drawings, Figure 1 illustrates 25 a diagrammatic lay-out of the apparatus required for one construction of the invention in the vicinity of the home and distant signal. Figure 2 shows diagrammatically the apparatus provided on the train 30 and the circuit connections while Figure 3 is an amplification of Figure 2 giving the mechanical features in greater detail; Figure 4 illustrates diagrammatically a modification of the train control system shown in 35 Figure 1 embodying the principles of the present invention. Figures 5, 6, 7 and 8 illustrate in greater detail the time element device shown diagrammatically in Figure 4.

Referring to Figure 1, the rails of the 40 track are represented by the references 1, 2, while the distant and home signals which are manually controlled are represented by the reference letters D and H respectively. To the left of the home signal a short length 45 of track constituted by the rails 3 and 4 is isolated from the main track, said isolated section having a battery 5 connected across the rails at one end, and a track relay 6 connected across the rails at the other end. Adjacent the track and in a suitable position 50 to engage with shoes on the passing engine are four ramps 7, 8, 9, 10 while T represents a time element device for the purpose of ascertaining the speed of the train between the ramps 8 and 9 i. e. whether the speed exceeds or falls below a certain speed 55 according to the time taken to pass from ramp 8 to ramp 9.

The same element device T consists of an 60 electromagnet 11 having an armature 12 which is adapted to pull up immediately the electromagnet is excited and close contacts 13 and 14. The attraction of the armature 65 places a tension on the open helical spring 15 so that a force is exerted on the toothed

sector 16 pivoted at 17 to cause this to rotate. The toothed sector 16 is geared with a pinion 17a coupled on the same shaft as a spur wheel 18 which gears with a pinion 19 on a shaft carrying a fly or air brake 20; 70 the sector 16 can only rotate comparatively slowly and therefore some time will elapse before the contacts 21 and 22 are closed. If for any reason the electromagnet 11 should become de-energized, the armature 12 tends 75 to resume its normal position under its own weight and thereby the sector 16 is permitted to return to normal also under gravity control. It should be mentioned that secured to the sector 16 is a leaf spring 23 80 adapted to engage with the adjustable contacts 24 and 25. The purpose of these adjustable contacts is two-fold. Firstly, they control the initial energizing circuit for the electromagnet 11, and secondly, they adjust 85 the length of travel of the sector 16 so that the time taken for the arm 16 to travel from its normal to its operated position may be adjusted within a considerable range to suit various speeds of the train or various 90 lengths of track over which the speed of the train is to be regulated. The contacts 26 and 27 are controlled by the starting and home signal levers respectively, the full 95 lines showing the position of the contacts when the signal levers are in their normal position and the dotted lines showing the position of the levers when in the operated position. The contacts 28 and 29 are provided in connection with single line working only and are operated to the positions shown in full lines or dotted lines respectively, according as to whether the direction 100 of running is from right to left as illustrated or in the reverse direction. When 105 used for double line working, the terminals 30 and 31, and 32 and 33 are connected together as shown by the lines of dots, while when used for single line working the connection shown by lines of alternate dots and dashes are used.

Before describing the operation of the 110 system, a description will be given of the apparatus provided on the engine, and for this purpose, reference should be made to Figures 2 and 3.

The principal apparatus comprises an 115 electromagnet 34 which controls by its armature 35 a valve 36 which when open admits air to the vacuum chamber 37 thereby causing a full application of the brakes. In addition an electromagnet 38 is provided adapted to control by its armature 39 120 the valve 40 which when open permits a restricted amount of air to pass through the opening 41 and the reed 42 into the vacuum chamber 37, thereby causing partial application 125 of the brakes and the emission of a warning signal to the driver. Other apparatus comprises a battery 43. A bell 44, 130

- restoring plungers 45 and 46 and a device 47 for resetting the valve 36 on its seat; a reversing switch 48 adapted to be controlled either by the position of the engine reversing gear or by the direction of the rotation of the axles is provided for switching over the electrical connections to the shoes 49 and 50 in accordance with the direction of running.
- 10 The shoes 49 and 50 are identical in construction and are provided one on each side of the engine. They are pivoted at 51 and 52 respectively and are adapted to be deflected either away from or towards the train according to the shape of the ramps. On each of the shoes is mounted an insulated contact plate 56 with which three brushes 53, 54 and 55 normally engage, so that these are normally all in contact. When however, the shoes are deflected to the right or to the left, one of the brushes 54 and 55 is isolated in the insulated gap 57 in the contact plate 56. The reason for this will be understood when the operation of the system is described. Having generally described the apparatus employed, a description will now be given of the operation of the system and later on a description will be given of the operation of certain details of the invention which are important in providing a thoroughly reliable and practical system of train control.
- It will be assumed in the first case that a train is approaching in the direction shown by the arrow and that both the distant and home signals are clear. In such circumstances, battery 58 will be connected direct to ramp 7 through armature 59 of track relay 6 and its working contact, and contacts 26 and 27 in their dotted position, terminals 30 and 31. When the engine approaches ramp 7, it will be noted that the shoe 49 will be deflected towards the train so that the brush 55 will be isolated. Now, normally, the electromagnet 38 is energized in the following circuit: positive pole of battery 43, lead 60, contact device 61 (which will be described later) brush 53, contact plate 56, brush 55, right hand winding of electromagnet 38 and winding of electromagnet 66^a and armature 67 in parallel, contact 62, armature 39, contact 63 to negative pole of battery 43. It will thus be appreciated that the electromagnet is normally energized and the effect of this energization is to maintain valve 40 closed. However, when arm 49 is deflected, this normal energizing circuit is broken, but as the ramp 7 is connected to battery 58, a circuit may be traced through the shoe 49 and its support 64 through the left hand winding of the electromagnet 38 to the frame of the engine and thence to the rail 2 to negative pole of battery 58, the electromagnet 38 is therefore maintained energized so that the armature 39 cannot fall away and there will be no partial application of the brakes at this point. The electromagnet 66^a is however de-energized and at its armature 67 closes a circuit for the bell 44 which may be traced as follows:— 70 Positive pole of battery 43, bell 44, armature 67 and its right-hand contact, contact 62, armature 39, contact 63 to negative pole of battery 43. The bell 44 therefore rings and indicates to the engine-man that he has 75 passed the distant signal and that the signal is at "clear."
- When the train reaches the ramp 8, the shoe 50 will be engaged. Under this condition, a circuit is closed for the electromagnet 11 as follows:—Positive pole of battery 43, lead 60, supporting bracket 65, shoe 50, ramp 8, terminal strap 32, 33, contact 25, leaf spring 23, contact 24, electromagnet 11 to rail 2 and frame of engine to which 80 the negative pole of battery 43 is connected. Electromagnet 11 is thereby energized but is immediately de-energized when the train leaves ramp 8 due to its normal locking circuit from battery 58 being broken at contact 26, the time element device being therefore without effect. This locking circuit extends from rail 2, over battery 58, armature 59, contact 26, lead 69, contacts 13, 14, electromagnet 11, back to rail 2. When the 85 train reaches ramp 9, the shoe 49 is deflected outwards and the contact 54 is therefore isolated, so that the normal energizing circuit through the left hand winding of the magnet 34 is broken, this circuit being 90 traced as follows:—Negative pole of battery 53, contact 65^a, armature 35, contact 66, left hand winding of electromagnet 34, brush 54, brush 53, contact device 61, lead 60 to positive pole of battery 43. As however, a 95 circuit is completed from positive pole of battery 58, armature 59 and its working contact, contacts 26 and 27 in the operated position, terminal straps 30 and 31, ramp 9, shoe 49, support 64, right hand winding of 100 electromagnet 34 to the frame of the engine and thence to rail 2 and negative pole of battery 58, electromagnet 34 is maintained energized and the valve 40 remains closed. On 105 passing the ramp 10 exactly the same circuits are completed the ramp 10 being connected to battery 58 through armature 59 and contacts 26 and 27 in their operated position. When the train passes over the 110 rails 3 and 4, the track circuit relay 6 is de-energized, thereby breaking battery connection with the ramps 7, 9 and 10: subsequently the home and starting signals are returned to the normal or danger so that the connection of battery 58 with the ramps 7, 9 and 115 10 is broken at contacts 26 and 27. 120
- It will next be assumed that the home and distant signals are at "danger" when the train is approaching. Consequently, when the shoe 49 engages with the ramp 7 and 130

is deflected inwards, battery 58 will be disconnected from the ramp 7 and therefore there will be no circuit for the left hand winding of the electromagnet 38, and as 5 the circuit of the right hand winding and the winding of relay 66^a is broken at brush 55 the armature 67 will fall away and armature 39 will be released, thereby permitting the valve 40 to open and allowing air 10 to enter through the opening 41 and past the reed 42.

The effect of this is to give a partial application of the brakes thereby somewhat restricting the speed of the train, and at the 15 same time, by causing the reed 42 to vibrate due to the passage of the air, a warning signal is given to the driver. As the armature 39 has been forced upward by the pressure of the outside air on valve 40, the circuit 20 for the bell 44 will not be completed. It will therefore be appreciated, that by this means a different signal is given to the engine man according as to whether he is passing a distant signal at "danger" or at 25 "clear".

The engine man can remove the partial brake application by pressing on the diaphragm 46 thereby closing the contact springs 68 so that once the shoe has been 30 stored to normal the circuit of the right hand winding of the magnet 38 is again completed from positive pole of battery, lead 60, contact device 61, brush 53, contact plate 56, brush 55, right hand winding of 35 electromagnet 38, contact 68 to negative pole of battery and the armature 39 attracted to close the valve 40. If desired, arrangements could be provided whereby this restoration of the armature 39 and the 40 removal of the partial brake application could only be effected if the engine man had himself taken steps to apply the brakes. Such an arrangement is not described as 45 means for bringing the idea into effect may be readily developed by those versed in the art.

The restoration of the armature 67 of the electromagnet 66^a can be effected by pressing the diaphragm 45 as will be readily understood by reference to Figure 3.

The engine next approaches the ramp 8 where the shoe 50 is deflected inwards. In this position, the circuit will first be completed as before described for the electromagnet 11 which attracts its armature 12 and at contacts 13 and 14 closes a locking circuit which may be traced as follows:— 55 Battery 58, armature 59, and its working contact, contact 26 in its position shown in 60 full lines, lead 69, contact 13, armature 12, contact 14, electromagnet 11 to rail 2 and back to negative of battery 58. Electromagnet 11 is therefore maintained energized until either the starting or both the starting 65 and home signal levers are operated to

the clear position or until the train passes over the track 3 and 4 and short circuits the track relay 6, so that the armature 59 falls away. Armature 12 by its attraction puts a tension on the open helical spring 15 70 to cause the toothed sector 16 to rotate about its pivot 17; consequently, the sector 16 commences to travel slowly towards contacts 21 and 22. The first effect of this is the opening of leaf spring 23 of the initial energizing circuit of the electromagnet 11 through contacts 24 and 25. If the train exceeds a given speed for which the distance between the ramps 8 and 9 is chosen and the time element device T is set, it will 80 reach the ramp 9 before the contacts 21 and 22 are closed.

Consequently when the shoe 49 is deflected outwards by the ramp 9, there will be no flow of current from the ramp through the 85 right hand winding of the electromagnet 34 and as the left hand winding will be de-energized due to brush 54 being isolated, the armature 35 will fall away and the valve 36 will open to admit air to the vacuum chamber 37 and cause a full emergency application of the brakes. If on the other hand, the train was traveling below the predetermined speed, then the sector 16 would have 90 engaged with the contacts 21 and 22 and battery 58 would be connected in the following 95 circuit to the ramp 9; battery 58, armature 59 and its working contact, contact 26 in the normal position corresponding to the danger position of the signal, lead 69, contact 13, armature 12, contact 14, contact 22, toothed sector 16, contact 21 to ramp 9, shoe 49, bracket 64, right hand winding of 100 electromagnet 34, to frame. Electromagnet 34 would therefore be maintained energized, and consequently the brakes would 105 not be applied.

It will be seen that in case a train should be present in the section of track 3, 4, when shoe 50 engages ramp 8, the track relay 6 would be de-energized and consequently the locking circuit for magnet 11 would be opened at armature 59. Consequently, in this case contacts 21 and 22 cannot be closed however slowly the train is proceeding and a full emergency application of the brakes will take place at ramp 10 as described above.

When the train approaches the ramp 10, 110 as this ramp depends solely for its connection to battery on the operation of both the home and starting signal levers, it will be evident that as this ramp is shaped identical with the ramp 9, there will be a full brake application whether or not there has been a 115 full brake application at ramp 9. Usually, the ramp 10 will be placed at the home signal and adapted to pull up trains travelling below a certain speed within the block clearance, while trains exceeding that speed will 120 125 130

be tripped at the ramp 9. Obviously, additional ramps to suit various speeds could be provided in addition to the ramps 9 and 10, but it is thought in practice two will be sufficient. It will also be noted that whenever the home and starting signal levers are operated to the "clear" position, battery 58 is connected direct to the ramps 9 and 10 and therefore the train has a free passage and can speed up without any possibility of the brakes being applied.

As soon as the train passes over the rails 3 and 4, the track relay 6 is short circuited and at 59 the battery connection to the ramp 9 is broken and also the time element device is de-energized and restored to normal in readiness for the passing of the next train. An important feature of this construction is that the ramp 9 is always in the "danger" condition except for the short interval which elapses between the time when the train passes the ramp 9 and the time when it reaches the rails 3 and 4. The time element device is first energized by a supply of energy on the train (battery 43); is subsequently maintained energized independently thereof by a second source of energy (battery 58); and is subsequently permitted to restore to normal immediately the latter source of energy is removed. Further its restoration being under gravity control, there is no danger of broken springs or the like preventing its return. It will be obvious that that part of Figure 1 which includes the ramps 8 and 9 the time element device T and the small insulated track section 3 and 4 may be utilized independently of the signalling system in any place where a permanent speed reduction is required, for instance, it may be applied at the turn out of a junction or where the configuration of the line is on a sharp curve; the circuit arrangements would such a case simply consist of a straight connection from the front contact of armature 59 direct to contact 13, and the contacts 26 and 27 would be eliminated.

For single line working, it will be understood that a set of ramps similar to the ramps 7, 8, 9 and 10 would be provided at each end of the track and consequently, in order to prevent the ramp 8 becoming equivalent to the ramp 7 for the reverse direction of running a special lever 28, 29 is provided which takes the positions shown in full lines for the direction of running described and the position shown in dotted lines for the reverse direction of running. It will thus be appreciated that in the reverse direction of running, the ramp 8 is connected direct to battery 58 and consequently the brakes will not be applied to the train running in the reverse direction when passing the ramp 8, and further, the connection between the terminals 30 and 31 will be broken. Special

interlocking means would be provided to ensure conformity between the position of the special lever with the starting and home signal levers.

It will be understood that the brakes will be controlled in the usual way for trains running in the direction for which the ramps are set. In case of engines travelling in the reverse direction, say for instance, tender first, then obviously it is desirable to reverse the current connections to the shoes, and this is effected by means of a reversing switch 48 with movable contact arms 70—74. As before mentioned, the shoes 49 and 50 are of identical construction and as these are provided with four different contacts one of which is used for two different purposes according to the direction of running a switch having 5 contact arms is required. The reversing switch may be conveniently controlled in accordance with the direction of rotation of the axles or with the position of the engine reversing gear. Consequently, the arrangement of the ramps 7, 8, 9, 10 shown in Figure 1, will control the application of the brakes in the manner described for trains running in the direction of the arrow whether tender first or otherwise, while by providing the special lever controlling contacts 28 and 29 only that set of ramps which respond to the direction of running will be operative to control a train for single line working.

Referring to Figure 3 a brief description will be given of various details for carrying out the invention in a preferred manner. For instance, in order to render the valves 36 and 40 and also the special valve 75 the purpose of which will be described later, as effective as possible, they are provided with a comparatively sharp engaging surface adapted to embed on to rubber rings 76, 77 and 78 respectively. Consequently, very little force other than that required to overcome the pressure of the outside air will be required to ensure an effective seal. The valve 40 is adapted to be replaced on its seating by the simple attraction of the armature 39 which is allowed a comparatively limited movement this being possible in view of the valve 40 being provided for applying a partial brake application only.

The valve 36 is to apply the full brake application and it is only to be applied in cases of emergency; it is necessary that this valve should only be replaced with considerable difficulty and that the operation must take some considerable time. This is effected by the mechanism 47 which consists of a handle 79 cranked to a shaft 80 on which is fitted a small pinion wheel 81 geared with a large toothed wheel 82 secured on the shaft of the special valve 75 having a threaded portion 83 engaging with the frame to ensure a vertical movement of the valve on

rotation. The operator in order to replace the valve 36 on its seating has to turn the handle 79 thereby opening the valve 75 until its end 83 engages with the armature 35 and forces this armature upwards and also forces the valve 36 back on to its seating 76; the armature 35 being restored to normal completes at contacts 65^a and 66 the circuit of its normal energizing winding which 5 therefore holds the armature 35 in its operated position and maintains the valve 36 closed. The brake application however is not yet removed as the chamber 37 is open to the atmosphere through the valve 75 and 10 ports 100 in the cover on the gear 82; it is still further necessary for the engine driver to rotate the crank 79 so as to bring the valve 75 back on to its seating 78. It will 15 therefore be appreciated that it is practically impossible for the engine driver to remove the brakes until they have been on for a sufficient length of time to bring the train to a standstill. If desired the arm 79 could be 20 secured with a seal so that a record would be given whenever it was used or a record 25 could be made in any other convenient way.

Another feature of the invention is the construction of the shoes 49 and 50. As previously mentioned these shoes are normally pivoted at 51 and 52 so as to move at right angles to the direction of the running of the train. The bearings supporting the shoes are in turn mounted on horizontal shafts 84 and 85 at right angles to the direction 30 of the running of the train, on which shafts are fitted springs 86 engaging with collars 87 thrusting these collars against the sides of the bracket 89 fixed to the engine. Interposed between the collars 87 and the 35 bracket 89 are friction discs 88 so that the bracket supporting the shoe 51 is enabled to rotate about the shaft 84 but only after overcoming considerable friction. On the bracket 89 is secured a contact device 61, having a fixed contact 90 and a movable contact 91 which latter contact is adapted to be actuated by the rod 92 which passes through holes in the main frame and in the friction 40 disc 88 into a recess in the flange of the shaft 84, so that whenever the shaft 84 is moved from normal position, the rod 92 is forced out of the recess in a longitudinal direction and causes the contact 91 to break connection with the contact 90. As this contact device 61 is in the normal energizing 45 circuit of the magnet maintaining the valves 36 and 40 closed, it will be appreciated that if the shoes 49 and 50 strike obstacles with sufficient force to cause the shoe 49 to rotate other than in the direction effected by the ramps, then the brakes would be immediately applied. Buffer springs at 93 and 94 are provided to maintain the shoe 49 normally in a central position.

65 Referring to the accompanying drawings,

Figure 4 illustrates diagrammatically the operation of the train control system embodying the principles of the present invention; Figure 5 shows a sectional elevation of the improved time control element, Figure 6 shows a side section with mechanism and coils removed, Figure 7 shows an inverted plan with the base removed, while Figure 8 shows a side sectional elevation.

70 Before proceeding with the description of the operation of the system, the construction of the time control device illustrated in Figures 5-8 will first be explained.

The time control element consists of an 75 electromagnet 120 controlling an armature 121. This armature 121 is pivoted at 124 and is provided with an arm 123 having a curved surface 125 on one side and a projecting member 126 on the other side which 80 normally engages with a projection 127 on the shaft 128 carrying the balance weight 129.

A shaft 130 pivoted in brackets 131 and 85 132 carries a ratchet wheel 133 and a cylindrical disc 134, while a bracket 135 loosely supporting a roller 136 in close proximity to the surface of the disc 134 is pivoted on the shaft 130. Normally the roller 136 under gravity control rests in the position 90 shown, although this position may be adjusted by the screw 137 to the left of that shown. When the electromagnet 120 is excited, the armature 121 with its arm 123 moves a short distance sufficient to permit the projections 126 and 127 to disengage so 95 that the balance weight 129 can commence to swing. At the same time the arm 123 moves the roller 136 into engagement with the surface of the disc 134. This movement is sufficient to break the connection between 100 the contacts 138 and 139 (Figure 6) and the resting contacts 140 and 141 respectively, but not sufficient to permit the contacts 142 and 143 to make connection with their 105 working contacts 144 and 145 respectively. 110 The release of the balance weight 129 causes this member with the shaft 128 to swing to and fro.

115 As in a well known clock work movement a contact is closed for the electromagnet 146 in circuit with a primary cell through the balance spring 147, shaft 128, contact 148 (Figs. 4, 7 and 8) and contact 149 supported by a leaf spring and arranged so that the 120 shaft only makes electrical connection when moving in one direction. Electromagnet 146 as is well known serves to attract the soft iron pole piece carried by the balance weight 129 as this approaches its core so maintaining the balance weight in movement. On the shaft 128 is a cam 150 adapted to engage with a roller 151 supported on a bracket 172. The bracket 172 is pivoted at 173 and carries at its upper end a pawl 170 so that the cam 150 by acting on the 125 130

roller 151 causes the pawl 170 to advance the ratchet wheel 133 and with it the disc 134 one step for every complete swing of the balance weight 129. The movement of the disc 134 is imparted to the roller 136 which advances step by step between the surface of the cylindrical disc 134 and the inner surface 125 of the arm 123 which is so shaped as to exert substantially uniform pressure on the roller 136 during its movement.

After a predetermined time the roller 136 advances to a position opposite recess 152 where the arm 123 can move freely and permit the armature 121 to complete its movement and cause the contacts 142 and 143 to engage with the working contacts 144 and 145 (Figure 6). When the electromagnet 120 becomes de-energized the arm 123 falls back to its normal position releases the roller 125 which immediately is restored to normal by gravity and permits the projecting member 126 to engage with the projection 127 when the balance weight 129 reaches the position shown in Figure 5 of the drawings. It will be noted that the projection 127 is cam shaped in order to prevent any damping of the movement of the balance weight 129 so that it is assured that the member 129 will by its inertia, reach the position in which it is to be locked ready for a re-operation of the device.

In Figure 4 it will be noted that an arm 122 is shown engaging at its extreme end with the member 129 at its outer edge, and while this serves for diagrammatic purposes, such a construction is not desirable nor is it found to be so satisfactory in practice as that shown in Figure 5. It might be mentioned that all the working parts shown in Figures 5, 6, 7 and 8 are supported by means of brackets 177 and 178 from the cover 153 of a box 154 having glass faces 155 by which the operation of the parts may be observed for inspection purposes. The cover 153 is provided with a number of terminals by means of which connection may be made both to the contacts and to the electromagnets 146 and 120. In order to render the construction weatherproof a rubber or like gasket 156 is provided between the lid 153 and the box 154. The bracket 177 and 178 carries ball bearings 175 and 176 respectively on which the shaft 128 can oscillate with negligible damping.

A modification of the train control system described with reference to Figs. 1, 2 and 3 will now be described. This system differs from the previous system in that, in place of ramps, mechanical train stops are used such as are described, for instance, in British Patent No. 6807/14; while the initiation of the operation of the time control device is effected by a circuit being

closed by the train between a short insulated rail and another rail. Another feature is the arrangement of the circuits by which the time control device illustrated in Figs. 5, 6, 7 and 8 is arranged to operate in a train control system having the features of the invention. Referring to Fig. 4, DS represents the distant signal and H represents the home signal adjacent a length of track over which it is assumed that it will be desirable to control the speed of the train. At the home signal H, starting signal X, and advance starting signal Y, train stops TS are fitted, while at a point somewhat in advance of these train stops is an auxiliary train stop ATS. The train stops may be of any well-known construction which involves a mechanical engagement with apparatus on a train except that the train stop ATS must be electromagnetically controlled. The train stop TS may be either electromagnetically controlled or mechanically controlled and is adapted to be brought to the "off" position only when the corresponding signal shows "clear." The apparatus on the train is well known and need not be described, one example of it being given in the British Patent No. 6807/14, above referred to.

The auxiliary train stop is located at a position which is determined by the local conditions. It is assumed that a certain block clearance is allowable beyond the home signal H in which a train must pull up as to pass beyond this limit when the signal is at "danger" is to run the danger of an accident. Consequently if the train is travelling below a certain speed the train stop TS would be able to bring it to rest within the block clearance, but if the train is exceeding a certain speed, then the auxiliary train stop ATS must come into action and the position is so chosen that if a train is going at its maximum possible speed it will always be pulled up within the block clearance past the home signal if the brakes are applied by the train stop ATS.

If desirable of course, other auxiliary train stops could be provided to correspond to intermediate speeds, but in practice one auxiliary train stop will usually be all that is desirable. The speed of the train is estimated by means of a time element device comprising a neutral relay R and a time control device TC which is represented diagrammatically and is illustrated in greater detail in Figures 5-8. This time element device serves to determine whether the time taken for the train to pass over a measured track which extends from the insulators 101 to the auxiliary train stop ATS is less or greater than a predetermined amount.

On the right hand side of the insulator 101 on the upper rail, a short insulated rail

- 110 is fitted in the main track. This insulated rail is electromagnetically connected to a battery B and to the armature 112 of the relay R. The rail 111 which extends 5 from the insulator 101 to the left of the rail 110 beyond the auxiliary train stop ATS to the insulator 113 is also insulated and is electromagnetically connected to the working contact 114 of the armature 112. 10 BW represents the block wire which extends from one signal cabin to the next in series with polarized relay PR. This relay can only operate when the direction of current in the block wire corresponds to the 15 signal "train on line" having been set up. Under these circumstances armature 116 is attracted and a circuit extends from rail 117 through armature 116 and its working contact, relay R, battery B to insulated rail 20 110. This circuit obviously cannot be completed until a train connects the rail 110 with the lower rail 117.

It will be assumed that the signals are at "danger" and the train has advanced beyond the distant signal. Under these circumstances the engine-driver should have reduced the speed of the train according to instructions. But whether or not he has done so, as soon as the front wheels of the 25 train pass beyond the insulators 101; the rails 110 and 117 are electrically connected together and the relay R is energized in the previously traced circuit. The relay then attracts its armatures 112, 118 and 119. At 30 armature 112 it completes a locking circuit for itself independent of the rail 110 which may be traced as follows:—Rail 117, armature 116 and its working contact, relay R, battery B, armature 112 contact 114, to rail 111 which is now connected by the train to the rail 117. The relay R therefore remains 35 energized until the last carriage of the train passes beyond the insulator 13. At its armature 119, a circuit is closed for the electromagnet 120 of the time control device TC as follows:—Positive pole of battery B', electromagnet 120, armature 119 and its working contact to negative pole of battery B'. The electromagnet 120 energizes and 40 attracts its armature 121. This armature is provided with two arms 122 and 123, the arm 122 corresponding to the projection 126 (see Figure 5), while the arm 123 is substantially identical to that described with 45 reference to Figures 5-8. The consequence is that the balance weight 29 is released and commences to oscillate under the control of the electromagnet 146. By means of its cam 150, the balance weight 129 causes the 50 roller 151 by means of the pawl 170 to advance the ratchet wheel 133 step by step and to rotate with it the cylindrical disc 134. As the arm 123 has also moved sufficiently to 55 force the roller 136 into engagement with both the surface 125 of the arm 123 and the

surface of the cylindrical disc 134, the roller advances and after a predetermined time comes opposite the recess 52 when the armature 121 is no longer prevented from moving to its fully attracted position to engage 60 with the contacts 144 and 145 when a circuit is closed as follows: positive pole of battery B², contact 144, armature 121, contact 145, contact 155, controlled by auxiliary train stop ATS, winding 157 of the electromagnet 75 controlling said train stop, armature 118 to negative pole of battery B' which is connected in series with battery B². The train stop magnet is thereby excited and its arm moved to the "off" position. Now if the 80 train had been exceeding a predetermined speed it would have reached the auxiliary train stop before this operation could have taken place as the time for the roller 136 to come opposite the depression 152 has been set to take a predetermined time according to the estimated speed which the train must not exceed; consequently the train on reaching train stop ATS would have its brakes applied. If, however, it has been travelling 85 below the predetermined speed, then it will not be affected and will only have its brakes applied if it passes the train stop TS. Normally the train should be pulled up at the 90 home signal but if it should pass the train stop TS, its braking will be automatically applied; however, its speed will not be high enough to allow it to travel beyond the block clearance under these conditions.

On the assumption that everything is clear, then all the signals governing the motion of the train (in addition to the home signal, the starting signal X and the advance starting signal Y are also shown) will be at the "clear" position. Contacts 160, 161 and 162 which represent contacts controlled in the well known manner at the signal levers will be closed and a circuit for the electromagnet 120 may be traced as follows: positive pole of battery B', electromagnet 120, 105 lower rail 117 contacts 160, 161 and 162 in the operated position to negative pole of battery B'; electromagnet 120 will therefore be energized as soon as the signals are lowered, so that before ever the train reaches 110 the rail 110 the roller 136 will have approached if not actually reached, the depression 152; consequently the armature 121 will make contact with contacts 144 and 145 some time before the train reaches the train stop 115 ATS. The circuit of the auxiliary train stop ATS however is not completed until relay R is energized as this is open at armature 18 and as this relay can only be energized by a train connecting rail 110 with rail 117, it follows that the auxiliary train stop will only be in an off normal position during the passage of a train over the rail 111. The auxiliary train stop ATS is provided 120 as usual with a contact operating device cor- 130

responding to its "off" and its "on" positions, the armature 155 being adapted when the train stop is in the off position to be withdrawn from connection with its resting contact as to bring into circuit a resistance 163 whereby the current consumption is reduced, it being understood of course that a considerably heavier current is required for energizing the train stop 157 than for maintaining it in its off position. Armature 164 is provided for detection purposes, positive or negative battery being connected by armature 164 from the rail 117 to an auxiliary conductor 165 extending to a detector DE 15 in the signal cabin, so that the position of the train stop may be observed.

It will thus be appreciated that by means of the present invention, a time element device has been produced which always 20 starts under the same conditions, which requires very little energizing current, just sufficient to cause the roller to engage between the disc and the auxiliary arm of the armature, while the timing is highly accurate and the exact amount can be adjusted by varying the starting position of the roller. A single dry cell is sufficient for maintaining the oscillator and under ordinary circumstances should last for several 30 years.

It will be appreciated that by means of the invention a system has been evolved which is reliable, adapted to interfere with the normal running of the trains as little 35 as possible, while providing a maximum amount of safety, and further, the apparatus used is simple while the time element device for determining the speed of the train is accurate and requires little operating current, thereby ensuring that the maintenance costs will be low.

It should be mentioned that the part of the invention comprising the track circuits, the electromagnetically controlled train stop 45 and the time element device with the neutral relay may be applied to any part of the line where a permanent speed reduction is required as on curves or the turnout of a junction, while the provision of two trainstops, one controlled in accordance 50 with the speed of the train may be provided at terminal stations to ensure that a train does not enter at too high a speed; such arrangements would of course be entirely independent of the normal signalling system.

What we claim and desire to protect by Letters Patent is:—

1. A train control system comprising a track, a time element device located at the 60 side of the track, apparatus controlled by said time element device for effecting the application of the brakes of a passing train, means controlled by a passing train for setting the said time element device in operation to control said apparatus to prevent the

application of the brakes if the speed of the train is below a certain value and manually operated signalling means operable to control said apparatus to prevent the application of the brakes if the track is clear. 70

2. A train control system comprising a track, apparatus located at two different points alongside said track for effecting the application of the brakes of a passing train, speed determining means for controlling the 75 apparatus which is located at that point which is nearer to an approaching train, means for controlling the apparatus which is located at that point which is further from the approaching train and manually operated signalling means adapted in addition to controlling a visual signal to control said apparatus so as to prevent the application of the brakes when conditions 80 are such that a train can pass without restriction. 85

3. A train control system comprising a track, apparatus located at two different points alongside said track for effecting the application of the brakes of a passing train, a time element device located at the side of the track and set in operation by the train to control, after a predetermined time, the apparatus which is located at that point which is nearer to an approaching train, means for controlling the apparatus which is located at that point which is further from the approaching train, and manually operated signalling means adapted in addition to giving a visual signal to control said apparatus when conditions are such that a train can pass without restriction. 95 100

4. A train control system comprising a track, apparatus located at two different points alongside said track for effecting the application of the brakes of a passing train, a time element device located at the side of the track and set in operation by the train to control, after a predetermined time, the apparatus which is located at that point which is nearer to an approaching train, manually operated signalling means for indicating if the track is clear or not, means under the influence of said signalling means to control said apparatus independently of said time element device, and means for controlling the apparatus which is located at that point which is further from the approaching train. 110 115

5. A train control system comprising a track, apparatus located at a given point alongside said track for controlling the application of the brakes of a passing train, a time element device adapted to be set in operation when a train passes a certain point and maintained in operation independently of its initial energizing source, a member movable under a continuously acting restoring force and adapted to be controlled by said time element device when in operation 120 125 130

to prevent said apparatus causing the application of the brakes if the train reaches a given point after a predetermined time, and releasing means controlled by the train on 5 passing another point to effect the restoration of the movable member to its normal position.

6. A train control system comprising a track, apparatus located at a given point 10 alongside said track for controlling the application of the brakes of a passing train, a member adapted to be operated against a continuously acting restoring force when a train passes a certain point and maintained 15 in operation, means under the control of the train after it has passed beyond the given point to permit the restoration of said member under the control of said force and a time controlling device adapted to be set in 20 operation by the first member also against a continuously acting restoring force to so affect said apparatus after a predetermined time as to prevent the brakes being applied.

7. A train control system comprising a 25 track, apparatus located at a given point alongside said track for controlling the application of the brakes of a passing train, an electrically controlled time element device adapted to have its circuit closed when a train 30 passes a certain point, circuit closing members adapted to be operated when said device is energized to close a point in an independent circuit for maintaining said device in operation, a movable member under a continuously 35 acting restoring force adapted to be controlled by said time element device when in operation to prevent said apparatus causing the application of the brakes if the train reaches a given point after a predetermined 40 time, and means for opening the circuit of the time element device when the train passes another point to affect the restoration of the movable member to its normal position.

45 8. A train control system comprising a track, a ramp located at a given point alongside said track for influencing the apparatus controlling the application of the brakes on a passing train, a second ramp located at a 50 second point alongside said track in the direction of an approaching train, an electrically controlled time element device adapted to have its circuit completed when a train passes the first ramp and maintained 55 in operation in an independent circuit, a movable member under a continuously acting restoring force adapted to be controlled by said time element device to complete a circuit to said second mentioned ramp and 60 thereby influence the brake controlling apparatus on the train if it has not reached the given point before a predetermined time to prevent the brakes being applied and means for opening the independent circuit when the 65 train passes another point to affect the res-

70 toration of the movable member to its normal position.

9. A train control system comprising a track, an electromagnet alongside said track, a contact member adapted to be engaged by a device on a passing train to complete an energizing circuit for said electromagnet, an armature for said electromagnet circuit closing members carried by said armature and adapted to close a point in an independent circuit for maintaining said electromagnet energized, a time element device adapted to be set in operation when said armature is attracted, means for controlling the application of the brakes of a passing train and means controlled by said time element device to render said brake controlling means non-effective after a predetermined time.

10. A train control system comprising a track, an electromagnet alongside said track, a contact member adapted to be engaged by a passing train to complete an energizing circuit for said electromagnet, an armature for said electromagnet, a time element device adapted to be set in operation when said armature is attracted, means for controlling the application of the brakes of a passing train, means including electrical circuit connections for controlling the application of the brakes of a passing train, and contact 90 making devices controlled by said time element device to make certain of said connections and thereby prevent the application of the brakes after a predetermined time.

11. A train control system comprising a track, an electromagnet alongside said track, an electrical circuit including said electromagnet and adapted to be completed by the passage of a train, a second electrical circuit adapted to be completed when said electromagnet is energized to maintain it energized independently of said first mentioned circuit for controlling the application of the brakes of a passing train, a time element device adapted to be set in operation when said electromagnet is energized, contact making devices controlled by said time element device to complete said circuit and prevent the application of the brakes after a predetermined time and circuit opening means controlled by a passing train to effect the opening of said second circuit to restore the time element device to normal.

12. A train control system comprising a track, an electromagnet alongside said track, an electrical circuit including said electromagnet and adapted to be completed by the passage of a train, a second electrical circuit adapted to be completed when said electromagnet is energized to maintain it energized independently of said first mentioned circuit for controlling the application of the brakes of a passing train, a time element device adapted to be set in operation when said 125

electromagnet is energized, contact making devices controlled by said time element device to complete said circuit and prevent the application of the brakes after a predetermined time, a short portion of track insulated from said first mentioned track and located beyond the point where the brakes are adapted to be applied, a source of electrical energy connected across the rails of said track, an electromagnet also connected across the rails of said track and adapted to be normally energized by said source of electrical energy, a contact adapted to be normally closed by said electromagnet to normally maintain the second circuit closed and to effect its opening when short circuited by a passing train.

13. A train control system comprising a track, apparatus located at a given point alongside said track for controlling the application of the brakes of a passing train, an electromagnet adapted to have its circuit completed when a train passes a certain point, circuit closing members adapted to be operated when said electromagnet is energized to close a point in an independent circuit for maintaining said electromagnet energized, means operated when the train passes a point beyond the given point for positively opening said independent circuit for said electromagnet and a time controlled device adapted to be set in operation due to the energization of said electromagnet and to operate against a continuously acting retarding force to so affect said apparatus after a predetermined time as to prevent the brakes being applied.

14. A train control system comprising a track, a ramp located at a given point alongside said track for controlling the application of the brakes of a passing train, an electromagnet adapted to have an energizing circuit completed when a train passes a certain point and to be maintained energized in a different circuit until the train has passed the given point, and a time controlling device adapted to be set in operation due to the energization of said electromagnet and to operate against a continuously acting retarding force, to connect a source of electrical energy to said ramp after a predetermined time for the purpose of preventing the application of the brakes.

15. A train control system comprising a track, a ramp located at one side of said track, an electrically controlled time element device connected to said ramp, and adapted to be set in operation when a train passes said ramp, a second ramp situated differently from said first ramp with respect to the track and arranged to control the application of the brakes of a passing train unless connected up to a source of electrical energy, and adapted to be so connected by said time element device after a predetermined time, a third ramp situated and adapted to function similarly to said second ramp and a circuit for connecting a source of electrical energy to said second and said third ramps independently of said time element device, the second ramp being located at such a position as to prevent a train passing a given point whatever its speed if the brakes are applied at that point, while the third ramp is located at such a position as to prevent the train passing the given point if the train has taken a longer time in passing from the first to the second ramp than the time element device has taken to operate.

16. A train control system comprising a track, a shoe on a passing train, a ramp at the side of said track for controlling the movement of said shoe in one direction so as to cause a partial application of the brakes and a second ramp at the side of said track for deflecting the shoe in another direction to cause the full application of the brakes.

17. A train control system comprising a track, a shoe on a passing train, a ramp curved so as to cause said shoe to be deflected in a horizontal direction at right angles to the track to cause the partial application of the brakes, and a second ramp curved in such a manner as to cause the shoe to be deflected in an opposite direction to the first ramp to cause the full application of the brakes.

18. A train control system, comprising a track, a ramp located alongside said track, speed determining apparatus adapted to be set in operation when the train completes a circuit through said ramp, and a second ramp on the other side of said track adapted to effect the application of the brakes unless the speed determined by said speed determining apparatus is less than a predetermined amount.

19. In a train control system, a locomotive having a shoe secured thereto and adapted to be deflected in different directions by ramps on the track, brake controlling apparatus controlled by said shoe to cause the full application of the brakes if the shoe is deflected in one direction and the partial application of the brakes if the shoe is deflected in the other direction.

20. A train control system comprising a locomotive a shoe secured to said locomotive and adapted to be deflected in different directions by ramps on the track, normally energized electromagnets for controlling the partial or full application of the brakes respectively and means for opening the circuit of one or other of said electromagnets to cause the full or partial application of the brakes according to the direction in which the shoe is deflected.

21. A train control system comprising a

locomotive two shoes secured to said locomotive one of which is adapted to be deflected in different directions by ramps on the track to cause either the full or partial application of the brakes while the other shoe is connected up to initiate the operation of speed determining apparatus.

22. A train control system comprising a locomotive, shoes located one on each side of said locomotive and adapted to be deflected in opposite directions, one of which controls the circuit of electromagnets controlling the application of the brakes while the other controls the circuit of speed determining apparatus, and switching means operable to change the electrical connections to the shoes in accordance with the direction in which the train is running.

23. A train control system comprising a track, an electromagnet alongside said track, an electrical circuit including said electromagnet adapted to be completed by the passage of a train, a quick moving armature on said electromagnet, a time control device, spring connecting means between said armature and said time control device, adapted to cause said time control device to be set in operation when said armature is attracted, while permitting the armature to make a movement independently of the time control device, means for controlling the application of the brakes on a passing train and means controlled by said time element device to make said brake controlling means non-effective after a predetermined time.

24. A train control system comprising a track, an electromagnet alongside said track, an electrical circuit including said electromagnet adapted to be completed by the passage of a train, a quick moving armature on said electromagnet, a time control device, a spring connecting said armature to said time control device to cause said device to be set in action when said armature is attracted, means for controlling the application of the brakes of a passing train and means controlled by said time element device to render said brake controlling means non-effective after a predetermined time.

25. A train control system comprising a track an electromagnet alongside said track, a ramp alongside said track, an electrical circuit connecting said electromagnet with said ramp and adapted to be completed by a passing train to cause the energization of said electromagnet, an armature for said electromagnet contacts on said armature adapted to close a point in an independent circuit for maintaining said electromagnet energized, a time controlled device adapted to be set in operation when said armature is attracted, means for controlling the applications of the brakes of a passing train and

means controlled by said time element device to render said brake controlling means non-effective.

26. A train control system comprising a track, a ramp located alongside said track, an electrically operated time control device alongside said track, circuit connections extending between said ramp and said time control device and adapted to be completed by a passing train, a second ramp also alongside said track adapted normally to effect the application of the brakes, a source of electrical energy and contact making members adapted to be closed when said time element device has been in operation a pre-determined time to connect said source of electrical energy to said ramp and thereby prevent the application of the brakes of a passing train.

27. A train control system comprising a track, a ramp located alongside said track and adapted to be controlled to cause the partial application of the brakes of a passing train irrespective of the speed of the train, a second ramp located alongside said track and adapted to be controlled to effect the full application of the brakes if the train exceeds a certain speed and a third ramp also located alongside said track adapted to be controlled to effect the full application of the brakes whatever the speed of the train.

28. A train control system comprising a track, a ramp for controlling the partial application of the brakes of a passing train, a second ramp for initiating the operation of speed determining apparatus, a third ramp adapted to control the full application of the brakes if the speed of the train is greater than a certain amount as determined by said speed determining apparatus, and a fourth ramp adapted to control the full application of the brakes irrespective of the speed of the train.

29. A train control system comprising a track, a ramp for controlling the partial application of the brakes, a second ramp for initiating the operation of a time control device, a third ramp for effecting the full application of the brakes when the train reaches said third ramp before the time element device is fully operated, and a fourth ramp controlling the full application of the brakes.

30. A train control system comprising a track a ramp located alongside said track and adapted to be controlled to cause the partial application of the brakes of a passing train irrespective of the speed of the train, a second ramp located alongside said track and adapted to be controlled to effect the full application of the brakes if the train exceeds a certain speed and a third ramp also located alongside said track adapted to be controlled to effect the full application

1 of the brakes whatever the speed of the train, and means for connecting a source of electrical energy to said ramps to prevent the application of the brakes being effected.

5 31. A train control system comprising a track, a ramp located alongside said track causing the partial application of the brakes, a second ramp located in a different position with respect to said track for initiating the 10 operation of speed determining apparatus and a third ramp shaped differently from said first ramp to cause the full application of the brakes of a passing train if the speed of the train is greater than a predetermined 15 amount.

32. A train control system comprising a track, a curved ramp located at the side of said track for controlling the partial application of the brakes, a second ramp curved similarly to said first ramp on the other side of said track for initiating the operation of speed determining apparatus, and a third ramp located similarly to said first ramp but curved in an opposite direction with respect to said track for controlling the full application of the brakes as determined by said speed determining apparatus.

33. A train control system comprising a ramp adapted to control the partial application of the brakes, a second ramp, an electromagnet, circuit connections extending between said ramp and said electromagnet and adapted to be completed by a passing train to cause the energization of said electromagnet, an armature controlled by said electro-

magnet adapted to operate contact members whereby said electromagnet is connected in a holding circuit independent of said second ramp, a time controlled element set in operation by said armature when attracted, contact members adapted to be connected up when said time controlled element has operated for a predetermined time, a third ramp for causing the full application of the brakes, circuit connections extending from said third ramp to said contacts controlled by said time controlled device to prevent the full application of the brakes if the train has taken longer to pass from the second ramp to the third ramp than the time taken for the time controlled element to operate, a fourth ramp for controlling the full application of the brakes, signal controlling means, contact devices operated by signal controlling means to connect a source of electrical energy to said first, third and fourth ramps to prevent the application of the brakes if the signals are operated, and circuit opening means controlled by a passing train to open the holding circuit of said electromagnet to permit said electromagnet to become de-energized and the time element device to return to its normal position.

Signed by me at Liverpool, England, this 12th day of October, 1921. 65

ALFRED ERNEST HUDD.

Signed by me at Liverpool, England, this 12th day of October, 1921.

ARTHUR FRANK BOUND.
